United States Patent Office

Des. 218,355
Patented Aug. 11, 1970

218,355

CANDELABRUM OR THE LIKE

Martin B. Bloom, 2543 Randy Lane, and Terry I. Feit, 2765 Bell Road, both of Bellmore, N.Y. 11710; and
Irving J. Mandel, 10 Avondale Road, Plainview, N.Y.
11803

Filed Jan. 17, 1969, Ser. No. 15,402

Term of patent 14 years

Int. Cl. D26—05

U.S. CL. D48—2

FIG. 1 is a front view of a candelabrum or the like showing our new design;

FIG. 2 is a side view thereof; and
FIG. 3 is a top view thereof.

We claim:

The ornamental design for a candelabrum or the like, substantially as shown.
